UNITED STATES PATENT OFFICE.

BERTHOLD HUBER, OF TAUNTON, MASSACHUSETTS.

STOP-CYLINDER PRINTING-MACHINE.

SPECIFICATION forming part of Letters Patent No. 300,370, dated June 17, 1884.

Application filed July 6, 1883. (No model.)

To all whom it may concern:

Be it known that I, BERTHOLD HUBER, a citizen of the United States, residing at Taunton, in the county of Bristol and State of Massachusetts, have invented a new and useful Improvement in Stop-Cylinder Printing-Machines, of which the following is a specification.

My invention relates to an improvement in the mechanism used for stopping and starting again the cylinder in a stop-cylinder printing-press. In this class of printing-presses the cylinder obtains its motion during the largest part of each revolution from the bed alone, while the bed may be driven by the ordinary crank-motion or by any other suitable mechanism. While on the impression or forward stroke of the bed the cylinder is geared directly to the bed; but on the return-stroke of the bed the cylinder stands still, continuing its intermittent motion constantly in one direction on the next forward stroke of the bed. In order to let the rack on the bed, which gears directly with the gear on the cylinder, return without again moving the cylinder, the teeth on the cylinder are cut away at that part of the cylinder-gear which is lowest during the period of non-rotation of the cylinder. In order that the cylinder may be brought to rest at exactly the same place at the end of every forward stroke of the bed, and enter into action with the rack exactly at the commencement of every forward stroke, it is necessary to provide the cylinder with a stopping and starting mechanism, or its equivalent. Such a mechanism usually consists of one or more cams, which, by means of one or more rollers working therewith and suitable connecting-rods, actuate a forked lever. The cams are of such shapes and the lever is so forked that the duty of the lever shall be to embrace a roller projecting from the end of the cylinder-gear as the cylinder nears the end of the stroke and is about to free itself from the rack on the bed, shall hold the cylinder, when at rest, in exactly the same position every time, in order to insure accurate register, while the bed makes its return-stroke free of the cylinder; and, lastly, shall, at the commencement of the next forward stroke, start the cylinder forward again, thereby bringing the cylinder-gear and

bed-rack into action, whereupon it shall free itself from the roller on the cylinder-gear and shall return to its central position ready to take and stop the cylinder once more on the completion of its stroke. Owing to the fact that there is a large amount of energy stored in the cylinder as it nears the end of its stroke, which has to be absorbed, and that an equal amount of energy has to be imparted to the cylinder in starting it from rest and before the rack on the bed takes it, and since this energy has to be absorbed by and then given back to the cylinder by the cams moving the forked lever, it has been found by experience that the wear on the cams, rollers, levers, &c., has been very detrimental to the accurate working of the machine, thereby preventing accurate register, and injurious to the life of the machine, thereby causing frequent repairs. As the energy to be absorbed and then to be given back to the cylinder increases with the square of the velocity, and consequently the wear of parts in the same proportion, such mechanism can only be used advantageously at low speeds, thereby precluding the use of a stop-cylinder press for fast work.

The object of my invention is to remove the largest part of the strain due to the energy of the cylinder from the cams, rollers, levers, &c., and put it in a place more capable of receiving it, the result being that there is but little, if any, wear to the cams and intermediate parts; and the press can, in consequence, be run with considerable increase of speed and with a greater degree of economy. I accomplish this very desirable feature by absorbing the energy of the arriving cylinder by a cushion or buffer device, and by imparting to the starting cylinder the same amount of energy by the reverse operation. By regulating the energy taken up and given out again by the cushion or buffer the amount of strain on the cams, &c., can be made as small as can be desired, and the cams will become simply time-keepers for the cushion or buffer with reference to the cylinder. The cushion or buffer may be of any of the well-known forms, such as are used to arrest the motion of moving parts; and the style of cushion or buffer actually used on a press forms no part of my in-

vention, as a plunger working in an air-cylinder, or any one of the many styles of air, coiled wire, or other springs now in use, which are capable of absorbing the momentum of a moving body and of afterward restoring it, may be used with advantage. In the drawings I have represented the cushion or buffer as consisting of steel-wiresprings coiled around rods, as such a form of cushion, I have reason to believe, is the most efficient and economical.

To further describe my invention, reference is made to the accompanying drawings, in which similar letters refer to corresponding parts.

15 Figure 1 of the drawings represents the general arrangement of a stop-cylinder press of the class I have reference to, with the outer frame removed in order to show more plainly the operating mechanism, and how that some 20 of the teeth of the cylinder-gear are cut away to allow of the passage of the rack on the bed. Fig. 2 is a side elevation of the same machine with one form of my improvement applied to it. Fig. 3 is a cross-sectional elevation of Fig. 2, the line of section being taken through the cylinder, forked levers, and bed-rack pinion B⁴. Fig. 4 is an end elevation of the same. Figs. 5, 6, and 7 show my improvement, as applied in Fig. 2, in some of the different positions 30 taken during a complete stroke of the bed. Fig. 8 is a side elevation of the same press, with the lever mechanism connecting the buffer with the forked lever somewhat varied. Fig. 9 is a plan of the same with the cylinder 35 and bed removed. Fig. 10 is a side elevation, and Fig. 11 is a plan section, of another variation in the application of my invention to the same machine, in which the buffer only acts on the cylinder in one direction.

40 A' A² are side frames; A³, foundation; A⁴, the feed-board. C' is the cylinder, having on its end the cylinder-gear C², part of whose teeth are cut away sufficiently to allow the bed B' to return when the cut-off part of gear C² presents itself to the rack B² on the side of the bed. C' is a tooth or roller projecting out from the cylinder-gear C², and in such a position that when the cylinder is at rest while the bed is returning the center line of the roller will 45 be in the center of the cut-off part of the cylinder-gear and vertically below the center of cylinder. As the cylinder nears the end of its stroke the forked lever C⁴, swinging about stud C⁵ in side frame, A', comes forward and 50 engages with the roller C³. The lever C⁴ obtains its motion from the cams C⁶ and C⁷, placed on the crank-shaft C⁸, by means of the connecting-rod C⁹, one of whose ends is fastened to the lower end of lever C⁴ by means of 55 stud C¹⁰, and the other end embraces the crank-shaft C⁸ between the two cams C⁶ and C⁷, and has rollers C¹¹ and C¹² projecting from its outer and inner sides, respectively, and of such size and position relative to each other that they 60 are constantly in contact with cams C⁶ and C⁷, respectively. The cams C⁶ and C⁷ are so pro-

portioned that by means of rollers C¹⁰ and C¹¹, connecting-rod C⁹, and stud C¹², the lever C⁴, swinging about stud C⁵, shall, as the cylinder nears the end of its stroke, go forward, and by means of its forked end embrace the roller C³, and, as soon as the gear C² and rack B² go out of action, gradually and gently bring the cylinder to rest with the roller C³ always in the same position vertically under the center 70 of cylinder, shall then hold the cylinder in that position until at such a time as the bed B' begins to go forward again, when the lever shall forcibly start the cylinder forward and shall not let go of the roller C³ until the gear C² and rack B² come into action once more, whereupon the lever shall return to the central position of its travel ready to again go forward, embrace the roller C³, and bring the cylinder once more to rest at the end of the stroke 75 which it has just started it upon. The crank-shaft C⁸ runs in two bearings—one, C¹³, in side frame, A', and the other in the bracket C¹⁴. Inside of bracket C¹⁴ and firmly keyed to shaft C⁸ is the crank-gear C¹⁵, which obtains its motion from the gear C¹⁶, fastened on the main driving-shaft G' of the press. By means of a connecting-rod, C¹⁷, forked at one end to embrace the bed-rack pinion B⁴, and engaging at the other end with crank-pin C¹⁸, projecting 80 from the outer face of the gear C¹⁵, the motion of gear C¹⁵ is transmitted to pinion B⁴. The bed-rack pinion consists of an ordinary gear, B⁴, gearing below with a rack, B⁵, fastened to the foundation A³, and above with the rack 85 B⁶, fastened to the under side of bed B', and of two flanges or rollers, B⁷, of a diameter equal to the pitch diameter of the pinion, and rolling on flanges or roller-ways B⁸, placed on each 90 side of the rack and on the level of the pitch line of the rack B⁶. The object of the roller-ways is to support the weight of the pinion B⁴, to guide it, and to keep the pinion at the proper distances from the racks B⁵ and B⁶. Since the pinion B⁴ meshes with a fixed rack, 95 B⁹, any amount of forward or backward motion imparted to it at its center by means of the connecting-rod C¹⁷ engaging the crank-gear C¹⁵ will produce double the amount of motion at the upper end of a diameter perpendicular to the rack; hence the bed B' and bed-rack B⁴ move twice as fast as the center of the pinion B⁴. 100

So far I have described simply the ordinary form of a stop-cylinder press, and lay no claim 105 to any part as so far mentioned.

On the shaft of cylinder C', produced outside of frame A', is fastened a disk, D', carrying a roller, D², projecting from it, and in the same plane of the roller C³ and the center line of cylinder. Embracing this roller D² is a slotted lever, D³, swinging freely about the stud C⁵. The slot in the lever D³ is straight and of such length that the roller D² cannot come in contact with either end of it. Therefore the rotation of the disk D', carrying the roller D², will simply result in causing the 110 115 120 125 130

arm D³ to swing forward and back from side to side. In Fig. 2 the slotted lever is shown at the extreme end of its motion, its center line being tangent to the path of roller D².

5 To the lower end of lever D³, by means of a stud, D¹⁰, is connected a rod, D⁴, which, passing freely through the block D⁵, is fastened to the block D⁶ by a nut on each side of the latter. Blocks D⁵ and D⁷ are connected by two 10 spring-rod, D⁸, passing freely through D⁶ and fastened to the blocks D⁵ and D⁷ by pins or by nuts outside of the blocks, whereby the strains on the springs may be adjusted. Around each 15 of the rods D⁸ are wound spiral springs D¹¹ and D¹². Through the center of block D⁷ passes a 20 crank-pin, D¹³, projecting from the outside of a disk, D⁹, fastened securely to the crank-shaft C¹ outside of the frame A'. It is evident that by 25 rotating the disk D⁹ and pin D¹³ to the outer or inner end of its throw a forward or backward 30 pressure will be exerted on the lower end of lever D³ by means of the intermediate rods and springs, and so through the roller D² on disk D⁷ to cylinder C¹. As the roller D² nears the 35 end of its stroke, the position of and pressure on the springs must be so arranged as to retard the cylinder and help bring it to rest; and since the springs must effectively exert 40 their pressure in starting the cylinder in exactly the opposite direction from what they did in stopping it, mechanism must be used to reverse the direction in which the pressure of the springs is to be exerted. In Fig. 2, as has been pointed out, the lever D³ is at the 45 extreme end of its side motion; and as roller D², sliding in the slotted lever D³, nears the lowest part of its travel, so the crank-pin D¹³ approaches the extreme point to the left of its travel. Fig. 5 represents the position of 50 the parts as they exist when the cylinder has just come to rest. The lever D³ has combined with pin D¹³, to put a large amount of compression on springs D¹². While the bed is going back and the cylinder standing still, the 55 pin D¹³ rotates to the position shown in Fig. 6, compressing the springs D¹¹, which, pressing on the block D⁶, tend to force the lower end of D³ into the position shown in Fig. 7, and so start the cylinder forward. In the 60 drawings the compressing and releasing of the springs D¹¹ and D¹² is done by a crank-motion, as being the simplest way of doing it; but a better result can be obtained by replacing the disk D⁹ and pin D¹³ by a properly-shaped cam and rollers. Such a cam has the advantage over 65 the crank-motion that the amount of compression can be varied, and can be more accurately and quickly brought into action at the right time. In Figs. 8 and 9 the same arrangement 70 is carried out with the exceptions that the disk D⁹ and the crank-pin D¹³ are replaced by an eccentric, D⁹; that the springs are placed inside, and so more out of the way; and, lastly, that instead of D³ being connected to D⁴ by 75 one stud, D¹⁰, motion is transmitted from a bent slotted lever, D³, by a connecting-rod,

D¹⁴, to an arm, D¹⁵, fastened on the outer end of a shaft, D¹⁶, having one bearing in the frame A', and the other in the bracket D¹⁷, and by a lever, D¹⁸, fastened to shaft D¹⁶, and connected to rod D⁴. The chief advantage of this form of my invention consists in the springs being inside of the frames, and so out of the way while manipulating the press in printing. 70

It is easily seen how the same principles 75 and ideas might be arranged in a great variety of ways to suit the requirements of each and every individual press; but it is needless to point them out any further than has already been done. 80

As it is possible, of course, to use my device only in stopping the cylinder, or only in starting it, I have shown in Figs. 10 and 11 my improvement as arranged for starting the cylinder from rest. It will be noticed that it 85 is shown as acting on the inner connecting-rod, which conveys motion from the cams C⁸ and C⁹ to the forked lever C¹. The mechanism consists of the rods D⁸, having the starting-springs D¹¹ coiled about them, fastened, 90 as in Fig. 2, to blocks D⁵ and D⁷, and passing freely through block D⁶. Block D⁷, instead of being fastened to a crank-disk, obtains its motion by carrying on its prolonged part a roller, D¹⁵, acting with the cam D¹¹, attached 95 to the crank-shaft C¹. The block D⁶ is fastened to an overhanging projection of connecting-rod C⁶. From the foregoing description the *modus operandi* is easily perceived. I am fully aware that stop-cylinder presses are made 100 in which a large amount of the energy of the arriving cylinder is absorbed by an ordinary friction brake or shoe, thus easing the strain on the cams C⁸ and C⁹, and thereby somewhat preventing any excessive wear on that part 105 of them which stops the cylinder. Any of the above-described arrangements may be used with the brake device, and so aid, not only in stopping the cylinder, but also in starting it again; or some one of the above arrangements 110 may be used to simply start the cylinder while the brake is used to stop it. 115

As has been said before, I do not confine myself to the particular kind of cushion, buffer, or spring, as shown in the drawings, as 120 each one and all of the various styles and kinds of air, rubber, coiled wire, or other springs, cushions, or buffers now in use which are capable of absorbing the momentum of a moving body and of afterward restoring it 120 are applicable to and may be used with advantage on my device, nor yet to the particular kind of lever arrangement herein shown.

What I claim, and desire to secure by Letters Patent, is— 125

1. The combination, with the cylinder of a stop-cylinder printing-press, of a series of springs, or equivalent cushioning device, substantially as described, together with a crank, or an equivalent cam with one or more rollers, 130 and also suitable and proper connecting mechanism, substantially as shown, and so arranged

as to help to relieve the pressure on the cams which stop and start the cylinder, substantially as shown.

2. The combination, with the cylinder of a stop-cylinder printing-press, of a disk, D', on cylinder-shaft, roller D², slotted lever D³, working therewith, connecting-rod D⁴, together with a series of springs or equivalent cushioning device, substantially as described, the connecting-piece D⁵, the crank-disk D⁶, and pin D⁷, or an equivalent cam with one or more rollers, substantially as described, and for the purpose set forth.

3. The combination, with the crank-disk D⁶

and pin D⁷, or an equivalent cam with one or more rollers, together with connecting-piece D⁵, of a series of springs or an equivalent cushioning device, substantially as described, connecting-rod D⁴, lever D³, studs D¹⁰ and C⁵, and having for its object the changing of the direction of the effective pressure of the springs or cushioning device, substantially as described. 15 20
